UNITED STATES PATENT OFFICE.

JOHN C. BROOKS, OF PATERSON, NEW JERSEY, ASSIGNOR TO DRAPER COMPANY, OF HOPEDALE, MASSACHUSETTS, A CORPORATION OF MAINE.

LOOM-SHUTTLE.

No. 842,133.

Specification of Letters Patent.

Patented Jan. 22, 1907.

Application filed September 28, 1905. Serial No. 280,446.

To all whom it may concern:

Be it known that I, JOHN C. BROOKS, a citizen of the United States, residing at Paterson, county of Passaic, State of New Jersey, have invented an Improvement in Loom-Shuttles, of which the following description, in connection with the accompanying drawings, is a specification, like figures on the drawings representing like parts.

10 This invention relates to loom-shuttles, and has for its object to provide a shuttle with a novel controller for actuating loom-stopping mechanism or some other loom-controlling mechanism, which controller is normally held in inoperative position, but is adapted to be thrown into operative position 15 when certain conditions arise that will make the weaving defective—such, for instance, as the exhaustion, or substantial exhaustion, of 20 the weft in the shuttle or the occurrence of a float in the warps, &c.

The controller is in the form of a member which is pivoted to the shuttle, and it is held in its inoperative position by a retainer 25 which is positively locked against movement, and the lock for the retainer is so arranged that whenever the abnormal conditions arise—as, for instance, whenever the weft is exhausted or a float occurs—the lock will be 30 actuated to release the retainer and the latter will be moved to release the controller, thereby permitting said controller to be moved into operative position, in which it sets in motion the loom-controlling mechanism.

35 In the preferred embodiment of my invention the lock for the retainer is adapted to be released both when the weft is substantially exhausted and whenever a float occurs, although it is not essential that the locking 40 device be arranged so as to be operative when either or both of these conditions arise.

In the drawings, Figure 1 is a top plan view of one shuttle-box of a loom and part of the breast-beam, said view also showing part of 45 the opposite shuttle-box. Fig. 2 is a top plan view of a shuttle embodying my invention. Fig. 3 is a side view thereof. Fig. 4 is a section, on an enlarged scale, on the line *xx*, Fig. 3. Fig. 5 is a section on substantially the line *yy*, Fig. 2. Fig. 6 is a detail view of 50 the controller. Fig. 7 is a detail of the locking mechanism for the retainer. Fig. 8 is a

right-hand end view of Fig. 7, and Fig. 9 is a section through the spindle and bobbin at the butt of the latter.

55 In the drawings, 3 designates the shuttle-box of a loom; 4, the lay; 5, the shuttle, and 6 the shipper-lever. These parts, with the exception of the shuttle, may be of any suitable or usual construction and form no part 60 of my present invention.

The shuttle is provided with a controller 7, herein shown as a member pivoted to the shuttle in the side thereof and adapted to be moved by a suitable spring or equivalent 65 means 8 from its inoperative position, such as shown in Fig. 2, wherein it lies within the walls of the shuttle, to its operative position, (shown in dotted lines, Fig. 2,) in which the outer end thereof projects beyond the shuttle and is in position to engage a suitable 70 loom-controlling mechanism as the shuttle enters the box.

The controller is normally held in its inoperative position by means of a suitable retainer 9, herein shown as a member pivoted 75 to the shuttle in some suitable way, as at 10. The controller is made with the hooked portion 11, which embraces the end of the retainer 9, and said retainer is shaped to present 80 a head 12 at its extremity and a neck portion 13. The head 12 is shaped to present oppositely-extending lips 14 and 15, the lip 14 being thinner than the lip 15, as best seen in Fig. 7.

85 Under normal working conditions the head of the retainer is so positioned in the hooked end 11 of the controller that the thinner lip 14 stands beneath the end of the retainer, while the thicker lip 15 projects through the 90 throat 16 of the controller and by its engagement with the walls of the controller forming the sides of said throat prevents said controller from turning movement about its pivot 17. If, however, the retainer 9 is depressed, 95 so as to carry the lip 15 entirely below the level of the controller, the latter is caused to swing about its pivot by the spring 8, and thus throw the free end 18 thereof into operative position, the neck 13 of the retainer at this 100 time occupying the recess 19 in the controller.

To prevent the retainer from being depressed, thereby to release the controller, except when the abnormal conditions arise, I

have provided a suitable locking-pawl 20, which is herein shown as being pivoted to the retainer and as normally engaging the upper side of the hook 11 of the controller, as seen in Fig. 7.

The neck of the retainer 9 is slotted, as at 21, to receive the locking-pawl when the latter is thrown into its inoperative position out of engagement with the controller. For actuating the locking-pawl to release the retainer I have herein shown a releasing-lever 22, which is pivoted either to the shuttle or to the retainer in any suitable way. Preferably, however, it would be pivoted on the pivot 10 of the retainer 9, and the retainer 9 will be slotted to receive the releasing-lever.

When my invention is to be used as a "float detector," I propose to locate the retainer and the releasing-lever 22 above the top of the shuttle, (shown best in Figs. 3 and 4,) so that whenever a float occurs the misplaced warps will by their engagement with the releasing-lever 22 depress the latter, thereby releasing the retainer and permitting the latter to be depressed by said misplaced warps until the controller 7 is released. In this case the releasing-levers 22 and retainer 29 constitute float-detecting members. Where the invention, however, is used for setting in motion certain loom-controlling mechanism or weft-replenishing mechanism when the weft in the shuttle has been substantially or completely exhausted, it is not necessary to place the releasing-lever and retainer above the side of the shuttle.

For operating the releasing-lever when the weft is substantially exhausted I have shown the outer end 23 of said lever as resting on the end 24 of a weft-controlled member 25, which is pivoted to the shuttle in any suitable way, as at 260. This member 25 has an arm 26 extending therefrom and provided with a projection 27, which engages a finger 28, carried by the shuttle-spindle and adapted to occupy a recess 29 in the bobbin 30. The weft on the bobbin is wound around outside the finger 28 and holds said finger within the recess, and said finger, acting against the projection 27 and the arm 26, holds the member 25 in its inoperative position. The end 24 of said member 25 is provided with a cam-surface 31, and said member is acted upon by a suitable spring 32, which tends normally to throw said member outwardly. Whenever the weft is exhausted, or substantially exhausted, from the bobbin, the finger 28 is released and the member 25 thrown outwardly by the spring 32. During this movement the cam-surface 31 acts against the right-hand end of the releasing-lever 22, thereby turning said lever about its pivot.

The initial turning movement of the releasing-lever actuates the pawl 20 and releases the retainer 9, and the continued

movement of said releasing-lever 22 brings the flanges 33 thereon against the top of the retainer 9 and depresses the latter sufficiently to release the controller.

In the present embodiment of my invention, therefore, the controller is released whenever either of two conditions arise—to wit, whenever the weft is exhausted and whenever a float occurs.

I believe I am the first to provide a shuttle with a controller which is constructed to be released when either one of two different conditions arises, and therefore I desire to claim this feature broadly. It is not essential, however, to the invention that the controller be arranged to be released when both of these conditions arise, as the invention could be embodied in a shuttle adapted to detect floats only or a shuttle adapted to operate the loom-controlling mechanism only when the weft is exhausted.

The controller is adapted to coöperate with any suitable loom-controlling mechanism, and for the sake of illustration I have herein shown such mechanism as comprising a trip 40 on the lay, which is connected by a rod 41 with a bunter 42, also pivoted to the lay. The bunter is normally held out of line with the shipper-lever 6 by means of a suitable spring 43; but whenever the controller is released it engages the trip and turns the latter so as to throw the bunter into line with the shipper, and when the lay beats up at the next turn said bunter throws the shipper out of the locking-notch, thereby stopping the loom. Any other loom-controlling mechanism may be employed, however, without departing from the invention.

Having described my invention, what I claim as new, and desire to secure by Letters Patent, is—

1. A shuttle, a controller carried thereby, means to hold the controller normally in inoperative position, and means to release the controller whenever the weft in the shuttle is substantially exhausted, or whenever a float occurs in the warp-threads.

2. A shuttle, a controller carried thereby, and means actuated either by the exhaustion of the filling or the existence of a float to actuate the controller.

3. A shuttle, a controller carried thereby, a lock to hold said controller in inoperative position, and means to release the lock when the weft is substantially exhausted or a float occurs.

4. A shuttle, a controller carried thereby, a retainer to hold the controller normally in inoperative position, and means to actuate said retainer thereby to release the controller whenever a float occurs.

5. In a shuttle, a controller, a retainer to hold said controller normally in inoperative position, and means to actuate said retainer

thereby to release the controller either whenever a float occurs or whenever the weft is substantially exhausted.

6. In a shuttle, a controller, a retainer to hold said controller normally in inoperative position, a locking-pawl to hold said retainer from movement, and means to actuate said pawl thereby to release the retainer whenever a float occurs.

10 7. In a shuttle, a controller, a retainer to hold said controller normally in inoperative position, a locking-pawl to hold said retainer from movement, and means to actuate the pawl to release the retainer by occurrence of a float or the exhaustion of the weft.

15 8. In a shuttle, a controller, a retainer to hold said controller normally in inoperative position, a locking-pawl to hold said retainer from movement, and means set in motion either by the existence of a float or the exhaustion of the weft to actuate the pawl thereby to release the retainer.

20 9. In a shuttle, a controller, a retainer to

hold said controller normally in inoperative position, a locking-pawl pivoted to the retainer and adapted to engage the controller, and a releasing-lever to actuate said pawl.

10. In a shuttle, a controller having a hook-shaped end and a pivoted retainer provided with a head to normally occupy the 30 throat of said hook-shaped end.

11. In a shuttle, a controller having a hook-shaped end, a pivoted retainer provided with a head normally occupying the throat of said hook-shaped end, a locking- 35 pawl carried by the retainer and adapted to engage the controller, and a releasing-lever for actuating said pawl.

In testimony whereof I have signed my name to this specification in the presence of 40 two subscribing witnesses.

JOHN C. BROOKS.
